FIG. 1

FIG. 1 is a front view of a doll embodying our new design.

FIG. 2 is a rear elevational view thereof.

FIG. 3 is a fragmentary side elevational view of the head and neck of said doll.

The characteristic feature of our design resides in the combination on the doll disclosed of the particular petal-like headdress suggesting a flower substantially as shown.

We claim:

The ornamental design for a doll or similar article, as shown and described.
